UNITED STATES PATENT OFFICE.

IVAR LUNDGAARD, OF HARTFORD, CONNECTICUT, ASSIGNOR TO THE AUTOMATIC REFRIGERATING COMPANY, OF HARTFORD, CONNECTICUT, A CORPORATION OF NEW JERSEY.

AIR-REFRIGERATING MACHINE.

Application filed May 22, 1922. Serial No. 562,905.

To all whom it may concern:

Be it known that I, IVAR LUNDGAARD, a citizen of the United States, and a resident of Hartford, county of Hartford, State of Connecticut, have invented certain new and useful Improvements in Air-Refrigerating Machines, of which the following is a specification.

My invention relates to a closed thermo-dynamic cycle useful in connection with air refrigeration, and also to the construction of an air refrigerating machine operating according to that cycle.

In a closed air refrigerating machine a body of confined air is alternately compressed and expanded, the compression taking place in one chamber and the expansion in another chamber. The two chambers are connected by a duct through which the mediating air is transferred. A regenerator may be employed between the compression and expansion chambers to form a part of the connection. The air in the expansion chamber is at a temperature below that of the body it is desired to refrigerate and the air in the compression chamber is at a temperature above that of the atmosphere or other body into which heat abstracted by refrigeration is to be discharged.

In my U. S. Patent No. 1,240,862, I have described an air refrigerating machine having a single cylinder equipped with a compression piston and a shifter piston for transferring the mediating air back and forth between the compression chamber and the expansion chamber through heat exchangers and a regenerator. The pistons are actuated by mechanism located in the crank case.

My present invention constitutes an improvement in the machine described in U. S. Patent No. 1,240,862 and has for one of its objects the utilization of a thermo-dynamic cycle that will combine a relatively high average pressure with a relatively low maximum pressure. This and other advantages I bring about by adopting a cycle in which the transfer of the mediating fluid from the compression to the expansion cylinder and the reverse is effected at substantially

constant pressure. Another object is to produce a machine in which a given body of air will serve as a mediating fluid without additions or subtractions, the purpose being to avoid the continual introduction of new air with its burden of moisture. Another object is to automatically establish the pressure during the cycle of operations so that the minimum pressure is atmospheric or slightly lower. Other objects will appear from the detailed specification.

I attain these objects by the construction of my machine and a consideration of the thermo-dynamic cycle will be given in connection with the accompanying drawings in which—

Figure 1 is a longitudinal vertical section taken through the centers of the two cylinders of my improved machine.

Figure 2 is a vertical section taken on line 2—2 of Figure 1 with the actuating mechanism in elevation.

Figure 3 is a sectional detail view of one form of compensating connection between the crank case and compression chamber.

Figure 4 is a diagram illustrating the changes in volume of the mediating air in the compression chamber and expansion chamber during one cycle.

Figure 5 is a diagram illustrating the changes in total volume of the mediating air during one cycle.

Figure 6 is a diagram illustrating the changes in pressure of the mediating air during one cycle.

Figure 7 is an indicator or pressure-volume diagram illustrating the work during one cycle.

Figure 8 is a diagram illustrating the relative movements of the compression piston and shifter piston during one cycle.

Referring more particularly to the drawings, Figures 1 and 2 show the construction of an air refrigerating machine, according to my invention, having two cylinders, each with its own body of mediating air, but it will be understood that any number of cylinders may be employed. A base 1 has attached to it a crank-case 2 by means of the bolts 3. Two cylindrical extensions 4 are

provided on the upper part of the crank-case 2. Concentric with and fitted to the upper surfaces of members 4 are heat exchangers 5. Regenerators 6, also concentric with members 4, are fitted to upper surfaces of heat exchangers 5. Cylinder heads 7 are in turn applied above regenerators 6 and heat exchangers 8 are mounted thereon. Cylinder head covers 9 are fitted above 5 and central with cylinder heads 7. Gaskets may be used between the various parts to insure tight joints and the parts are held in place by the clamping action of bars 10, channel 11, compression members 12, bolts 13, and nuts 14, by means of which the proper tension can be secured. Compression members 12 are of heat insulating material to prevent loss of heat from head covers 9. 10 Liners 15 are inserted in the upper parts of cylindrical portions 4 of the crank case and liners 16 are inserted within heat exchangers 5. The cylinder walls are, therefore, seen to consist of extension 4 of the 15 crank case, liners 15 and 16, regenerators 6, heat exchangers 8 and cylinder heads 7. At the upper end of liners 15 annular ports 17 lead to the heat exchangers 5 and at the top of heat exchangers 8, annular ports 18 20 connect with the cylinders at their upper ends.

The movements of the pistons will be described in connection with one cylinder, but it will be understood that the movements of 25 the pistons in the other cylinder are similarly performed. Compression piston 25 is actuated by a pair of links 26 pivoted at one end, one on each side of the axis of the piston. Links 26 are pivoted at their other 30 ends on the two walking beams 27, which rock about pin 28. Motion is imparted to walking beams 27 by connecting rods 29, the large ends of which work on crank pins 30 of crank shaft 31. A pulley 32 serves to 35 drive crank shaft 31. Shifter piston 40 comprises a cylindrical shell 41 of heat-insulating material attached to a bottom plate 42. A piston rod 43, secured to plate 42 by nuts 44, extends along the axis of the cylinder 40 through a bushing 45 in compression piston 25, through the crank case 2 and into a 45 guide bearing 46, which is secured to the bottom of the crank-case by nut 47. A spring seat 48 is attached to piston rod 43 by pin 49 and the lower ends of two links 50 50 are pivoted on pin 49. The upper ends of links 50 are pivoted at one end of cam lever 51, which rocks about pin 28. At the other end of lever 51, a roller 52 is mounted to rotate on pin 53 in contact with cam 54, which 55 forms part of crank shaft 31. A compression spring 55, acting between spring seat 48 and a depression in the crank case, serves 60 to keep roller 52 on the surface of the cam 65 and also to actuate shifter piston 40 in the

up direction. Cam 54 causes the downward movement of piston 40 and controls its upward movement.

Compression piston 25 is shown in its lowest position and it will be observed that 70 a passage 60 in the wall of piston 25 extends from the top of the piston to a point about half-way between the top and bottom, where it registers with a port 61 in the cylinder wall. A pipe 62 connects port 61 75 with chamber 63, from the lower portion of which a pipe 64 forms a connection into the crank-case. An inner container 65 may be provided in chamber 63 for calcium chloride or other drying agent and any air passing 80 through the chamber will come into contact with the drying agent.

Lubrication is afforded the moving parts by splash, the oil level in the crank case being indicated by line 66. 85

The operation of my improved machine will now be considered, assuming a direction of rotation of the crank shaft as indicated by the arrow. In the position shown, compression piston 25 is at its lowest position and shifter piston 40 is at its highest position. The space between the two pistons will be designated the compression chamber and the space above the shifter piston the expansion chamber. Port 61 in 90 the cylinder wall registers with passage 60 in piston 25 and the compression chamber is in communication with the crank case. Therefore, the pressures in the compression chamber and crank case will be equal. As 95 the crank shaft is rotated, piston 25 will move upward, thereby closing port 61, while piston 40 will remain stationary. This action results in compressing the mediating air in the compression chamber and some 100 of the air will flow through annular port 17 into heat exchanger 5, regenerator 6, heat exchanger 8 and the expansion chamber. A further rotation of the crank shaft causes 105 a continued upward movement of piston 25 and a downward movement of piston 40. By these combined motions of the pistons, the transfer of the mediating fluid from the compression to the expansion chamber at substantially constant pressure is effected. 110 It will be seen that the shifter piston is not held stationary until the compression is completed, as has been the case in previous machines of this type, but commences to shift the mediating fluid before the compression 115 piston has finished its stroke. The compressed air flows through heat exchanger 5 over leaves 19, which absorb heat due to the compression and transfer it to leaves 20 from which it is removed by a cooling fluid 120 circulating over them. From heat exchanger 5 the compressed air passes through regenerator 6 and heat exchanger 8 into the expansion chamber through ports 18. In heat exchanger 8, heat is absorbed by leaves 125 130

21 from a fluid to be refrigerated, which circulates over them by means of pipes 22 and 23. The heat absorbed is transferred to leaves 24 by conduction and is given up by 5 the leaves to the mediating air. Still further rotation of crank shaft 31 results in a downward movement of piston 25 and an equal downward movement of piston 40 resulting in an expansion of the mediating 10 fluid. The air is now entirely in the expansion chamber, with the exception of that contained in the heat exchangers and regenerator, and has been expanded which has lowered its temperature. Further rotation 15 of crank shaft 31 causes further downward motion of compression piston 25 and upward motion of shifter piston 40. The expanded air is thereby transferred back through the heat exchangers and regenerator 20 to the compression chamber which is accomplished at substantially constant pressure due to the combined motions of the two pistons. This completes one cycle. The exact relative motion of the two pistons will 25 be considered later in connection with a discussion of the thermo-dynamic cycle.

It is seen that a difference of temperature is established between the compression chamber and the expansion chamber. The 30 average difference of temperature is augmented by the regenerator, which has the power of absorbing heat and giving it up again as the temperature conditions during the cycle require.

35 It is very important in operating machines on this principle to exclude all moisture from the mediating air, as the moisture tends to collect in the cold end in the form of frost, which ultimately clogs the air passages and renders the machine inoperative. To prevent any moisture entering the machine, I construct the crank case and other parts so that all joints are completely tight and the only opening from the atmosphere 40 to the interior parts of the machine is the clearance around the crank shaft. To insure against air leaking either into or out of the machine, I provide an oil sealed stuffing box for the crank shaft. Spaces 75, filled 45 with suitable packing, are provided between solid bearing 76 and ball-bearing 77, around crank-shaft 31 (Figure 2). Between the two bodies of packing, a ring 78 slidably mounted on shaft 31, forms a pocket to contain oil. Ring 78 has recesses turned in its outer and inner surfaces, the recesses being in communication by means of radially drilled holes. Gland 79 in connection with bolts 80, serves to compress the packing in 50 spaces 75. An oil cup 81 acts as a reservoir to hold a supply of oil for maintaining the pocket within ring 78 filled, through passage 82. This oil also lubricates shaft 31. By the use of packing on both sides of ring 55 78, I keep the consumption of oil down to

an extremely low amount, and the leakage of air to a negligible amount.

It is to be noted that, with the construction as described, a definite body of air is contained within the machine, both as to 70 mass and identity. When the machine is not in operation, the pressure within the compression chamber, expansion chamber and crank case will be the same, since leakage by the pistons will equalize the pressure. I prefer to have the pressure substantially that of the atmosphere when the machine is idle, although a higher or lower pressure may be used since there is no communication to the atmosphere. When the machine is started up the pressure of the mediating air will alternately increase and decrease as the cycle of operations proceeds and the mediating air will be transferred back and forth through the heat exchangers and regenerator between the compression and expansion chambers. Since the latter are always in communication with each other, the pressure in all parts of the mediating air is always the same. 85

90 Assuming that there is no compensating connection from the space containing the mediating air to the crank case (as by passage 60 in piston 25, port 61, chamber 63 and pipe 64), it is apparent that after a few revolutions of the machine, the average pressure of the mediating air will equal that of the crank case, due to leakage past the piston 25. This average pressure will be substantially that of the atmosphere, if that pressure existed before starting up. For example, in machines I have constructed, I have found that if the greatest difference of pressure in the mediating air during the cycle 95 was ten pounds per square inch, it varied from five pounds below atmosphere to five pounds above atmosphere. 100

105 My compensating connection is provided to increase the average pressure of the mediating air. With piston 25 in its lowest position, the air is in the expanded condition and consequently at or near the lowest pressure. Therefore, if at this instant I connect the compression chamber to the crank case, the pressures will equalize by the flow 110 of air through pipe 64, chamber 63, passage 62, port 61, and passage 60. At all other times during the cycle, port 61 is closed by piston 25 and no air can flow through the compensating connection. By this means, air that leads past the piston into the crank case, during periods of high pressure in the mediating air, is returned to the mediating air each cycle at the time of low pressure. 115 I have found that, by the use of my compensating connection, the average pressure of the mediating air may be increased from atmospheric pressure to five pounds per square inch above atmospheric, while still maintaining ten pounds difference between maximum 120 125 130

and minimum pressure. This is an important advantage, as it increases the refrigerating capacity of the machine, due to the fact that a higher average pressure means a greater weight of air in the same volume.

When using the compensating connection, the pressure in the crank case will be slightly lowered during operation of the machine, since a certain amount of air has been transferred to the mediating air above piston 25 to provide for the increased average pressure. Due to the size of the crank case, this effect is, however, very slight, but is sufficient to insure that any leakage occurring along crank shaft 31 will be of oil into the crank case, instead of air out of it.

In a two cylinder machine, in which one piston is moving oppositely to the other, as illustrated in Figure 1, the total volume of air in the crank case is practically constant, so that there is no change of pressure due to piston movement, but merely a movement of the air from one side of the crank case to the other, as the pistons move up and down.

In Figures 4 to 7, I illustrate diagrammatically the variations in pressure and volume of the mediating air throughout one cycle, as I prefer to carry it out. One cycle corresponds to one revolution of the crank shaft and I have divided the operation into four periods, A, B, C and D, each representing one-quarter revolution. In Figure 4, the vertical distance from line X , X at any point, to the solid lines bounding the shaded area, gives the distance of the compression piston from its upper position, and the distance to the dotted lines, gives the distance of the shifter piston from its upper position, hence the vertical distance from line X , X to the solid and dotted lines respectively, represents the volume at any instant in the compression and expansion chambers. During period A, the mediating air is being transferred from the compression chamber to the expansion chamber. During period B, the mediating air is being expanded in the expansion chamber. During period C, the air is being transferred back to the compression chamber and during period D, it is being compressed.

In Figure 5, the total volume of the mediating air is shown and the vertical distance below line X' , X' represents the total volume at any point during the cycle. In Figure 6, the manner in which the pressure varies is shown and the vertical distance above line X'' , X'' , represents the pressure at any point. Considering Figures 5 and 6 together, it is seen that during period A, the air is transferred from the compression chamber to the expansion chamber at a constant pressure P . Due to a lowering of its temperature by the cooling heat exchanger and the regenerator, the air decreases in

volume from V_1 to V_2 . During period B, the air is expanded in the expansion chamber from pressure P to p and its volume increases from V_2 to V_3 , its temperature decreasing. During period C, the air is transferred back to the compression chamber at the low pressure p . Due to the action of the refrigerating heat exchanger and the regenerator the volume of the air is increased from V_3 to V_4 and its temperature rises. During period D, the air is compressed in the compression chamber from volume V_4 and low pressure p to volume V_1 and high pressure P , its temperature increasing.

My cycle, therefore, comprises expansion and compression and a heat change in the medium under isobaric conditions. I have found many advantages in constructing my machine to operate according to the above described cycle, which is accomplished by properly coordinating the movements of the compression and shifter pistons, as will be described in connection with Figure 8. One of the chief advantages over that of machines utilizing a cycle in which the transfer of the mediating air is carried out under conditions of constant volume, is the decrease in difference of pressure required between P and p for a given refrigerating capacity. This means a greater thermo-dynamic efficiency and a more even torque curve, and consequently less starting torque and less fly wheel weight. The parts may also be lighter as they are not required to withstand as great pressures. Furthermore, there is less leakage past the compression piston and around the piston rod of the shifter piston and also a lower mechanical loss.

The usual indicator diagram is given in Figure 7, and it shows the work done in compressing the mediating air and the work returned by the expansion. The area P , V_2 , V_3 , p is the work of expansion and P , V_1 , V_4 , p is the work of compression. The net work per cycle is given by the area V_2 , V_1 , V_4 , V_3 , and must be supplied by the driving motor or other driving mechanism.

In order that my machine may operate according to the above described cycle, it is necessary that the compression and shifter pistons have the proper relative motion. It is seen that the motion of the compression piston is imparted to it by crank pin 30, connecting rod 29 and walking beam 27 through links 26 (Figure 1). By plotting with rectangular coordinates, the motion of the compression piston with respect to time, as represented by the rotation of the crank shaft, we have curve D of Figure 8, in which the ordinates are piston travel and the abscissæ are degrees of rotation of the crank shaft. Line A, A represents the bottom of the stroke and line B, B the top of the stroke of the compression piston. Line C, C repre-

sents the upper limit of travel of the shifter piston and curve E gives the shifter piston travel plotted with respect to the rotation of the crank shaft. Therefore, the vertical distance at any point from line C, C to curve D represents the total volume of the mediating air at that point (neglecting the clearance volume) and the vertical distance between curves E and D represents the volume in the compression chamber, while the vertical distance from line C, C to curve E represents the volume in the expansion chamber.

The motion of the shifter piston is controlled by cam 54 acting through roller 52, lever 51, links 50 and rod 43. It will be readily understood that the motion of the shifter piston according to curve E is attained by properly profiling cam 54 so that, as the compression piston performs the motion corresponding to the sine curve D, the shifter piston remains stationary at its top position during the period from 0° to 120°, moves downward to meet the compression piston during the period from 120° to 180°, follows the downward motion of the compression piston during the period from 180° to 270° and returns to its top position during the period from 270° to 360°, which completes one cycle.

Although the embodiments as described present the novel features of my invention, other forms of construction are possible and fall within its scope.

I claim:—

1. The method of operating refrigerating machinery which comprises compressing a mediating fluid in a compression cylinder, transferring the mediating fluid from the compression cylinder at substantially constant pressure to an expansion cylinder by a shifter piston while continuing the motion of the compression piston.

2. The method of operating refrigerating machinery which comprises compressing a mediating fluid in a compression cylinder, transferring the mediating fluid from the compression cylinder at substantially constant pressure to an expansion cylinder by a shifter piston while continuing the motion of the compression piston, expanding the mediating fluid in the expansion cylinder and transferring the mediating fluid at substantially constant pressure from the expansion cylinder to the compression cylinder by a shifter piston while continuing the motion of the expansion piston.

3. The method of operating refrigerating machinery which comprises compressing a mediating fluid by means of a piston in a compression cylinder, transferring the mediating fluid from the compression cylinder through a regenerator at substantially constant pressure to an expansion cylinder by a shifter piston while continuing the motion of the compression piston.

4. The method of operating refrigerating machinery which comprises compressing a mediating fluid by means of a piston in a compression cylinder, transferring the mediating fluid from the compression cylinder through a regenerator at substantially constant pressure to an expansion cylinder by a shifter piston while continuing the motion of the compression piston, expanding the mediating fluid in the expansion cylinder and transferring the mediating fluid at substantially constant pressure from the expansion cylinder to the compression cylinder by a shifter piston while continuing the motion of the expansion piston.

5. In a refrigerating machine of the closed cycle type using a gaseous mediating fluid, the combination of a chamber having a hot end and a cold end, a piston for compressing the mediating fluid in said chamber, a shifter for transferring the mediating fluid from one end of the chamber to the other, a crank shaft having cranks connected to the piston and cams connected to the shifter, the contour of the cams and their angular relation to the cranks being such that the mediating fluid, by the combined action of the shifter and piston, is transferred from one end of the chamber to the other at substantially uniform pressure.

6. In a refrigerating machine of the closed cycle type using a gaseous mediating fluid, the combination of a chamber having a hot end and a cold end, a piston for compressing the mediating fluid in said chamber, a shifter for transferring the mediating fluid from one end of the chamber to the other, a crank shaft having cranks connected to the piston and cams connected to the shifter, a crank case supporting the chamber and containing the crank shaft and articulating mechanism, means for sealing the journal bearings of the crank shaft in the crank case and a passage from said crank case to the chamber for connecting the crank case with the chamber when the piston is in its position of minimum compression.

7. In a refrigerating machine of the closed cycle type using a gaseous mediating fluid, the combination of a chamber having a hot end and a cold end, a piston for compressing the mediating fluid in said chamber, a shifter for transferring the mediating fluid from one end of the chamber to the other, a driving shaft articulated with the piston and the shifter so that the mediating fluid by the combined action of the piston and shifter is transferred from one end of the chamber to the other at substantially uniform pressure.

8. In a refrigerating machine of the closed cycle type using a gaseous mediating fluid, the combination of a chamber having a hot end and a cold end, a piston for compressing the mediating fluid in said chamber, a

shifter for transferring the mediating fluid from one end of the chamber to the other, a crank shaft having cranks connected to the piston and cams connected to the shifter, 5 a crank case supporting the chamber and containing the crank shaft and articulating mechanism, means for sealing the journal bearings of the crank shaft in the crank

case and a passage from said crank case to the chamber for connecting the crank case 10 with the chamber when the piston is in its position of minimum compression, and means interposed in the connecting passage for abstracting moisture from the mediating fluid.

IVAR LUNDGAARD.
